HINGE

Robert A. Ross, Orange, N. J.

Application January 20, 1938, Serial No. 185,789

7 Claims. (Cl. 16—179)

This invention relates to a hinge construction.

One of the objects of this invention is to provide a hinge which is simple and inexpensive in construction, and which is sturdy and durable under conditions of rigorous use. Another object is to provide a hinge particularly adapted for mounting an automobile door, for example. Another object is to provide a hinge whose various parts may be secured to a door frame and door in such a manner that all portions of the hinge are concealed when the door is shut. Other objects will be in part apparent and in part pointed out hereinafter.

The invention accordingly consists in the features of construction combinations of elements, and arrangements of parts as will be exemplified in the structure to be hereinafter described and the scope of the application of which will be indicated in the following claims.

With reference to the drawing, in which is shown one embodiment of my invention,

Figure 1 is a perspective view of my hinge attached to a door and door frame;

Figure 2 is a horizontal section of the hinge in open position;

Figure 3 is a horizontal section of the hinge in its closed position; and,

Figure 4 is a sectional elevation taken along the line 4—4 of Figure 3.

Similar reference characters refer to similar parts throughout the several views of the drawing.

In many instances it is desirable for a door or other closure, because of its construction, to be movable bodily from its frame, in addition to being swingable therefrom. Hinges which have been provided to effect this double movement operate indifferently because of complication of parts and structural weakness, because of which the hinges become sprung and thereafter fail to function properly. Still other of these hinges are so bulky that they cannot be concealed. A further disadvantage lies in the fact that some hinges of this type do not effectively safeguard against bodily relative movement between the door and frame when the door is closed, and such movement permits the door to become unlatched and accordingly swing open inadvertently. Accordingly, it is another object of this invention to provide a hinge which obviates these difficulties in an efficient and practical manner.

With reference to Figure 1 of the drawing, a door frame 10 and a door 11 are hingedly connected by a hinge comprising an anchor butt plate generally indicated at 12 and a swinging

butt plate generally indicated at 13. Anchor plate 12 is secured to frame 10 as by screws 14, swinging plate 13 being secured to door 11 as by screws 15.

Anchor plate 12 is substantially channel-shaped in cross section, thus comprising a bottom portion 16, wall portions 17 and 18, and oppositely directed flange portions 19 and 20, which extend toward one another to leave a space or opening therebetween. Preferably anchor plate 12 is set into frame 10 so that the outer surfaces of flanges 19 and 20 are flush with the surface of the frame. A pin 22 is secured to anchor plate bottom 16 adjacent the left-hand end thereof, as viewed in Figure 1, this pin being provided for a purpose described hereinbelow.

Still referring to Figure 1, a sliding plate 23 is slidably disposed within channel-shaped anchor plate 12, and has in its left-hand end a slot 24, into which pin 22 fits when the sliding plate is moved to the left, the plate thus abutting against the pin to limit leftward sliding movement of sliding plate 23 in anchor plate 12, as viewed in the drawing.

Swinging plate 13 has a pintle receiving ear 25 formed on its left-hand end, as viewed in Figure 1, which fits between a pair of pintle receiving ears 26 and 27 formed on the right-hand end of sliding plate 23. A pintle pin 28 pivotally connects ears 25, 26 and 27, thus pivotally or swingably securing swinging plate 13 to sliding plate 23, and accordingly effecting a pivotal relation between anchor and swinging plates 12 and 13. A hole or slot 29 is formed in the right hand end of swinging plate 13, and pin 22 fits into this slot when the swinging and anchor plates are folded together.

From the above it will appear that door 11 may be moved bodily outward, i. e., to the right as viewed in Figure 1, by virtue of the sliding relationship between anchor plate 12 and sliding plate 23. Furthermore, door 11 may be swung or pivoted in conventional manner through the provision of the pivotal connection between the swinging plate and sliding plate 23. When the door is closed, however, and all of the plates are in folded or nested relationship wherein pin 22 extends through slot 29, relative bodily movement between frame 10 and door 11 is prevented by reason of the pin and slot, thus preventing inadvertent outward sliding movement of the door, which would cause it to become unlatched. The door might become unlatched because of the fact that it could slide outwardly along its hinged edge sufficiently to unlatch any bolt or locking

mechanism with which the other edge of the door might be provided. As pointed out, this is prevented by pin 22 and slot 29.

As viewed in Figure 2, frame 10 is provided with a recess 30, which houses an arcuate bar or guide hook 31, one end 32 of which is joined to the right hand end of anchor plate bottom 16 (as viewed in Figure 2) and the other end 33 of which extends to a point adjacent the outer surface 10a of door frame 10. The outer surface 10a of the door frame has a slot 34 (see also Figure 3) formed thereon adjacent sliding plate 23, and this slot (Figure 2) receives an operating bar 35 which preferably is integrally formed with swinging plate 13 and extends substantially at right angles thereto. The left-hand end of operating bar 35, as viewed in Figure 2, is slotted as at 36 and this slot preferably has a curved or beveled edge 37 (Figure 3), which bears against the right-hand surface of guide hook 31 (Figures 2 and 3) during opening movement of the door, as viewed in the drawing.

Preferably the free end 33 of the operating bar 35 is reduced and rests against bottom 16 of anchor plate 12, when the door is open, adjacent portions of operating bar 35 being disposed within a slot 39 (Figure 4) in anchor plate bottom 16.

When the door is opened, as shown in Figures 2 and 3, pivotal movement of door 10 separates anchor and swinging plates 12 and 13, causing withdrawal of pin 22 from slot 29, and causing curved edge 37 of operating bar 35 to engage the right-hand surface of guide hook 31, as viewed in the drawing. All points of engagement between the operating bar and the guide hook are fulcrums about which swinging plate 13, considered as a lever, pivot to withdraw sliding plate 23 to the right, as viewed in the drawing, from within anchor plate 12. When door 11 is completely open, as shown in Figure 2, operating bar 35 abuts against sliding plate 23 and anchor plate 12, thus checking further opening movement of the door.

When the door is closed, substantially a reversal of operations takes place, and the above-noted fulcrum points are now on the left-hand surface of guide hook 31, as viewed in the drawing. Thus operating bar 35 swings clockwise and its free end slides along guide hook 31, forcing sliding plate 23 to the left (Figure 3) until the anchor, sliding and swinging plates are nested. When the plates are in this position, all portions of the hinge are effectively concealed because preferably door 11 includes a flange 11a which covers frame slot 34. Likewise, when the door is open, as shown in Figure 2, substantially all portions of the hinge are concealed when viewed from the exterior, as door flange 11a substantially conceals the exposed portion of operating bar 35.

It may now be seen that door 11 is not only swingable out of frame 10 in the conventional manner, but is also bodily movable therefrom, the bodily movement being automatically effected by the swinging or pivoting movement. Furthermore, because of pin 22 and slot 29 (Figure 3) bodily movement is precluded when the door is shut. Also by reason of the rigidity and relative position of operating bar 35 (Figure 2) an effective door check is provided, thus obviating the necessity of providing the usual straps or other supplemental door checks. Still further, when the door is closed, no portions of the hinge are visible.

Thus I have provided a hinge which attains

the above noted objects in a thoroughly practical and efficient manner.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

1. A hinge comprising, in combination, an anchor butt plate, a swinging butt plate, a member slidably associated with said anchor plate, means pivotally mounting said swinging plate on said sliding member, and means including a hook and slotted bar associated with both of said plates which upon swinging of said swinging plate effects relative sliding movement between said anchor plate and said sliding member, said hook being immovably secured to said anchor plate.

2. A hinge comprising, in combination, an anchor butt plate, a swinging butt plate, a member slidably associated with said anchor plate, means pivotally mounting said swinging plate on said sliding member, and means associated with both of said plates which upon swinging of said swinging plate effects relative sliding movement between said anchor plate and said sliding member, said last-mentioned means including a hook-shaped part secured to said anchor plate and a cooperating bar having means operatively engaging said part and secured to said swinging plate.

3. A hinge comprising, in combination, an anchor butt plate, a swinging butt plate, said anchor plate being substantially channel-shaped in cross section, a substantially flat member slidably disposed within said anchor plate, means pivotally mounting said swinging plate on said member, and means for effecting relative movement between said anchor plate and said member, said last-mentioned means including a hook-shaped part secured to said anchor plate and a cooperating bar operatively engaging said part and secured to said swinging plate.

4. A hinge adapted to swingably connect a door to a door frame comprising, in combination, anchor and swinging butt plates secured respectively to said frame and door, a plate pivotally connected to said swinging butt plate and slidably mounted in said anchor plate, a hook-shaped part secured to said anchor plate and extending away from a side edge of the door frame substantially in the plane of the door when closed, a rigid part secured to said swinging plate and extending at right angles therefrom and having a slot through which said hook-shaped part extends for all positions of said swinging plate with respect to said anchor plate so that upon swinging movement of said swinging plate said parts coact to effect sliding movement of said sliding plate in said anchor plate.

5. A hinge adapted to swingably connect a door to a door frame comprising, in combination, anchor and swinging butt plates mounted respectively on said frame and door, a sliding plate pivotally connected to said swinging plate and slidably mounted in said anchor plate, a stationary element secured to and extending from said anchor plate and concealed in said door frame, and means integrally formed with said swinging plate and operatively engaging said element to effect sliding movement of said sliding plate as said swinging plate is pivoted.

6. A hinge for a door frame having a recess formed therein and a door mounted in said

frame, comprising, in combination, an anchor plate secured to said door frame adjacent said recess, a guide bar mounted on said anchor plate and extending into said recess, a swinging plate secured to said door, a sliding plate pivotally secured to said swinging plate and slidably mounted in said anchor plate, and a part secured to said swinging plate and immovable in relation thereto, said part having portions formed to engage said guide bar and effect sliding movement of said sliding plate upon pivoting of said swinging plate.

7. A hinge for connecting a door frame and a

door, comprising, in combination, an anchor plate secured to said door frame, a stationary guide bar secured to said anchor plate, a swinging plate secured to said door, a sliding plate pivoted to said swinging plate and slidably mounted in said anchor plate, and a part stationary with respect to said swinging plate but swingable therewith and operatively associated with said guide bar to effect relative sliding movement between said sliding plate and said anchor plate upon swinging movement of said swinging plate.

ROBERT A. ROSS.
